(57) **CLAIM**

The ornamental design for a combined golf tee and holder therefor, as shown and described.

DESCRIPTION

FIG. 1 is a top and front perspective view of the combined golf tee and holder therefor, embodying my design;
FIG. 2 is a top plan view thereof;
FIG. 3 is a front elevation view thereof;
FIG. 4 is a right side elevation view thereof;
FIG. 5 is a bottom plan view thereof;
FIG. 6 is a rear elevation view thereof;
FIG. 7 is a left side elevation view of thereof;
FIG. 8 is a top front perspective view showing the tee element in an alternate upright position within the holder element; and,
FIG. 9 is a top front perspective view showing the tee element in the upright position and the holder element in an alternative flexed position.

The broken lines are included for the purpose of illustrating portions of the combined golf tee and holder that form no part of the claimed design.
